Primary Examiner—Nelson C. Holtje*Assistant Examiner*—Antoine D. Davis*Attorney, Agent, or Firm*—James Creighton Wray[57] **CLAIM**

The ornamental design for a programmable additive controller, as shown and described.

DESCRIPTION

FIG. 1 is a top and front perspective view of a programmable additive controller showing my new design;

FIG. 2 is a front elevational view;

FIG. 3 is a left side elevational view;

FIG. 4 is a right side elevational view;

FIG. 5 is a rear elevational view;

FIG. 6 is a top plan view; and,

FIG. 7 is a bottom plan view thereof.

FIGS. 1 and 2 have been drawn on an enlarged scale with respect to FIGS. 3-7.

FIG. 1

FIG. 3

FIG. 2

FIG. 6

FIG. 7

FIG. 5
